METHOD OF SURFACE FINISHING ARTICLES

Ladis W. Ruppert, Cranford, N. J., assignor to
Western Electric Company, Incorporated, New
York, N. Y., a corporation of New York

Application October 11, 1933, Serial No. 693,123

2 Claims. (Cl. 41—24)

This invention relates to a method of surface finishing articles and in particular for simulating a hand hammered finish on articles of metal.

An object of the invention is to provide a method 5 producing on metal articles a simulated hand hammered finish in a simple, certain and rapid manner.

One embodiment of the invention contemplates the use of an ordinary power driven punch press 10 in which either the customary die block of the press or the ram head or both are provided with a special tool comprising a multiperforate block each of the perforations of which holds a special forming tool having a convex working surface. 15 In its simplest form such a tool may be thought of as a hardened steel ball or a short cylinder with a convexly curved working end. Such a block may contain a considerable number of such tools. A sheet of metal to be finished may be held between the working parts of the press and at each 20 stroke will receive a plurality of indentations. By moving the sheet between strokes the indentations will be distributed irregularly thereover, the regular distribution of any one set of indentations becoming imperceptible in the chance controlled 25 irregularity of distribution of successive sets.

Other objects and features of the invention will appear from the following detailed description of one embodiment thereof taken in connection with the attached drawing wherein the same reference numerals are attached to identical parts in the several figures and in which

Fig. 1 is a diagrammatic perspective broken view of the working ends of the die block and ram head of a conventional punch press with a tool 35 adapted to carry out the method of the invention mounted on the die block;

Fig. 2 is a detached perspective view partly broken away of a preferred form of the tool;

Fig. 3 is a similar view of a modified form;

Fig. 4 is a detached perspective view of another modified form;

Fig. 5 is a detached broken view in side elevation of a third form;

Fig. 6 is a perspective of a piece of sheet metal before treatment;

Fig. 7 is a similar view of the piece partly treated;

Fig. 8 is a detached view in elevation of a fourth 50 form, and

Fig. 9 is a detached view in perspective of a fifth form.

In practising the invention as herein disclosed, Fig. 1 shows diagrammatically the ram head 10 and die block 11 of a power driven punch press of

any convenient and approved construction. A special tool block 12 is supported on the die block. A cooperating block 13 may be attached to the bottom face of the ram.

The tool block 12 is provided with a plurality 5 of parallel vertical perforations 14. In each perforation 14 is positioned a tightly fitting cylindrical member 15 having a convexly rounded upper working face 16 and a flat bottom face 17. The cylindrical members 15 may be hardened throughout or the faces 16 may be hardened and the rest of the members treated to have maximum toughness. Each member 15 is supported on its flat face 17 by the top surface 18 of the die block 11, and is given lateral support if necessary by the 15 tool block 12.

In operation, a piece of metal 19 to be treated 20 may be taken by one corner with a pair of tongs for example and laid on the tool faces 16. The press is then started and having been so adjusted beforehand that at the lowest position of the ram, the distance between the bottom face of the block 13 and the faces 16 is less than the thickness of the plate 19, the under surface of the plate will be 25 plurally indented by the members 15. As the ram head rises, freeing the plate 19, the latter is turned and slid slightly and the next stroke of the ram produces another set of indentations. The regular rows and columns of the second set 30 of indentations will be irregularly related to those of the first set. A third set will lie irregularly with respect to the first two sets. This procedure is continued until in the judgment of the operator, the desired effect 20 has been produced. The 35 positioning of the internally regular identical successive sets of indentations relatively to each other is thus entirely haphazard or chance controlled.

If it is desired to produce the effect upon both 40 sides of the plate 19, the block 13 may be replaced by a tool similar to that on the die block, whereby both faces of the plate will be indented simultaneously.

Fig. 3 discloses a modified form of tool in which 45 the cylindrical members 15 in the block 12 are replaced by hardened spheres 21 which are supported on a hardened plate 22.

Fig. 4 discloses another modified form of tool 50 in which a block 12 is formed with integral rounded projections 23 which may be hardened to serve the purpose of the faces 16. Or the projections may be formed by welding or otherwise fastening independently preformed knobs upon a plane faced block.

In any one of the forms disclosed, the working faces 16 of the indenting tool are usually substantially equidistant at their apices from the coacting face of the block 13, but in some cases may 5 be made to vary slightly in this respect to enhance the resulting appearance of irregularity of the indentations.

In another form of the invention, Fig. 5, the tool may take the form of a roll 24 having a 10 plurality of radial recesses in which are seated either cylindrical members like those of Fig. 2 having working faces 16, or balls such as those in Fig. 3, or the roll may be made with integral projections analogous to those shown in Fig. 4.

15 In either case the roll 24 may be mounted in an appropriate rolling mill diagrammatically indicated in Fig. 5, such as is customarily used for rolling operations, to coact with a corresponding smooth roll 25, or the smooth roll 25 20 may be replaced by a roll similar to the roll 24 when it is desired to indent simultaneously both faces of a plate passed therebetween.

In this last arrangement it is also possible to operate on a cylindrical article if the roll 25 be so 25 mounted that the article may be slipped over the roll, as for example by making one bearing of the roll 25 removable.

A fourth form of tool may be composed of a 30 bundle of such cylinders as those shown at 15 in Fig. 1 held immovably together by a tight band 26 as shown in Fig. 8; and fifth form may be made by enclosing a plurality of balls 21 in a rigid tray 27 as shown in Fig. 9, the tray being

so proportioned that the balls are held rigidly against relative displacement.

The embodiments of the apparatus and the modes of practising the invention herein disclosed are illustrative merely and may be modified and departed from in many ways without departing from the spirit and scope of the invention as pointed out in and limited solely by the appended claims.

What is claimed is:

1. An article having a simulated hand hammered ornamental surface finish comprising several pluralities of indentations impressed into a surface of the article, the indentations of each plurality being regularly arranged with respect 15 to each other and each plurality being positioned at haphazard with respect to each other plurality and each plurality overlapping at least in part at least one other plurality.

2. A method of treating the surface of a malleable article to produce thereon a simulation of a hand hammered finish which comprises the steps of simultaneously impressing a regularly arranged plurality of indentations into a portion of the surface of the article and subsequently 25 impressing a second identically arranged plurality of indentations into a part of the same portion of the surface of the article, the second plurality of indentations as a whole being irregularly positioned at haphazard with respect 30 to the first plurality whereby an ornamental surface finish is produced on the article having the irregular appearance of a hand hammered finish.

LADIS W. RUPPERT.
